UNITED STATES PATENT OFFICE.

AXEL JORGENSEN, OF DES MOINES, IOWA.

MACHINE FOR BARBING FENCE-WIRE.

SPECIFICATION forming part of Letters Patent No. 280,629, dated July 3, 1883.

Application filed May 4, 1883. (Model.)

To all whom it may concern:

Be it known that I, AXEL JORGENSEN, of Des Moines, in the county of Polk and State of Iowa, have invented certain new and useful Improvements in Machines for Barbing Fence-Wire; and I do hereby declare that the following is a full, clear, and exact description of the invention, which will enable others skilled in the art to which it appertains to make and use the same, reference being had to the accompanying drawings, which form a part of this specification, and in which—

Figure 1 is a front view of my improved machine for barbing fence-wire. Fig. 2 is a rear view of the same. Fig. 3 is a detail view of the barb and strand holding parts in the act of twisting. Fig. 4 is a side view of the barbed wires, and Fig. 5 is a side view of the machine with part of the frame broken away.

Similar letters of reference indicate corresponding parts in all the figures.

My invention has relation to machines for barbing fence-wire; and it consists in the improved construction and combination of parts of the same, as hereinafter more fully described and claimed.

In the accompanying drawings, the letter A indicates the main shaft of the machine, which is journaled in suitable bearings and rotated by any suitable means. Upon this shaft is fastened an eccentric disk, B, which revolves between the bifurcated ends of an arm, C, at the upper end of which is formed a circular disk, D, through the center of which disk the strand-twisting shaft E passes. Disk D is fastened upon the face of the bearing F, in which the twisting-shaft rotates by means of two headed bolts, G, passing through curved slots H in the disk into the face of the bearing, the curved slots allowing the arm and head to be rocked by the drive-shaft and eccentric disk.

Two grooves, I, extend from diametrically opposite points upon the surface of shaft E in opposite parallel directions toward the interior of the shaft, and the strand-wires J are fed from suitable reels through these grooves out to the barbing mechanism, being twisted by the revolution of shaft E. This shaft is revolved by means of a segmental rack, K, which is fastened upon the upper end of an arm, L,

pivoted at its lower end upon the frame-work of the machine and rocked by means of the wrist-pin M of a crank, N, sliding in a longitudinal slot, O, in the arm. As the drive-shaft A revolves, upon which crank N is fastened, the wrist-pin, traveling up and down in the slot O, will rock arm L, and the rack K will revolve a pinion, P, turning upon the twisting-shaft alternately in opposite directions, and a disk, Q, fastened to and concentric with the pinion. A spring-pawl, R, is pivoted upon the other side of disk Q and engages a ratchet-tooth, S, upon shaft E, so that the shaft is revolved with the pinion when the rack is rocked to one side, while the pawl allows the pinion to be revolved in the opposite direction when the rack is rocked to the other side. Two vertically-slotted lugs or barb-holders, T, are fastened to the front of disk D, diametrically opposite each other, and serve to hold the barb-blank Y, and, as the disk is rocked or oscillated, to give it a preliminary bend, the barb being fed between the strand-wires and held by the slotted curved ends of the barb-holders. From the upper edge of disk D an arm, U, projects laterally, through the outer forwardly-bent end of which passes a set-screw, V, which bears with its lower end against the movable cutter W, which is fastened upon arm U, and which operates, in conjunction with the rigid cutter X, to clip the barb-wire which passes between the cutters into blanks of the proper length. It will thus be seen that as the strand-wires pass out at the ends of grooves I the barb-blanks are inserted between the two strands, cut off as arm C rocks to one side, and slightly bent as the arm rocks to the other side, whereupon the twisting-shaft is revolved, bending the barb around the wires and twisting the wires, which thereupon are wound upon a reel suitably arranged in front of the twisting mechanism.

Having thus described my invention, I claim and desire to secure by Letters Patent of the United States—

1. The combination of the shaft A, having eccentric disk B, bifurcated arm C, having disk D at its upper end, and having barb-holders T upon its face and barb-cutter W fastened to laterally-extending arm U, stationary barb-

cutter X, and strand-twisting shaft E, having grooves I and means for revolving it, as and for the purpose shown and set forth.

2. As an improvement in barbing-machines for fence-wires, the combination and arrangement of shaft A, eccentric disk B, bifurcated arm C D, barb-holders T, movable barb-cutter W, stationary barb-cutter X, shaft E, having grooves I and ratchet-tooth S, disk Q, spring-
10 pawl R, pinion P, arm L, having segmental

rack K and slot O, and crank M N, all constructed to operate as and for the purpose shown and set forth.

In testimony that I claim the foregoing as my own I have hereunto affixed my signature 15 in presence of two witnesses.

AXEL JORGENSEN.
